HAMMER MILL SCREEN CHANGING
MECHANISMArthur G. Nickle, Saginaw, Mich., assignor to
Nickle Engineering, Saginaw, Mich.

Application September 27, 1948, Serial No. 51,433

40 Claims. (Cl. 241—89)

1

My invention relates to a mechanism for automatically interchanging an idle screen with a working screen in a hammer type grinding mill by remote electrical control. More especially my invention is applicable to hammer mills used in custom feed-grinding plants that process ear corn and small grain to produce livestock feeds of any desired fineness. The hammer mills in general use in such plants are installed below the operating floor, so that the operator is compelled to travel up and down from one floor to the other to manually change the working screen when the fineness of the reduced material must be modified to suit individual customers. Such manual screen-changing operations not only entail extra work for the operator and a loss of valuable time, but a waste of mill power, especially so if the mill must be stopped and started to change the screen.

This invention provides an electrically controlled mechanism for removing the working screen from a hammer-grinding mill, which screen is one of a plurality of similar screens interchangeable therewith, and automatically replacing it by any idle screen selected from the plurality. To effect the screen interchange the operator simply presses the electrical pushbutton that is associated with the selected screen that is to be introduced into the mill housing. As the automatic screen interchange cycle involves a time interval of less than nine seconds, it will be apparent that this invention affords a valuable means for conserving time and mill power when the fineness of the reduced product must be modified.

A detailed description of this automatic screen-changing mechanism, as applied to a hammer mill grinding unit, is made with reference to the accompanying drawings in which is embodied one form of my invention.

Description of figures:

Fig. 1 is a side elevation of a hammer-grinding mill unit that embodies the automatic screen-changing mechanism.

Fig. 2 is a fragmentary plan view that corresponds to Fig. 1.

Fig. 3 is a fragmentary vertical transaxial sectional view through the grinding chamber of the mill which shows the grading screen clamped in working relation with the hammer rotative element and the idle screens mounted above the mill housing, the view being indicated by line 3—3 in Fig. 2.

Fig. 4 is an enlarged detail elevational view of a bellcrank employed in the screen-clamping mechanism.

2

Fig. 5 is an edge view of the bellcrank shown in Fig. 4.

Fig. 6 is a fragmentary vertical sectional view showing screen-clamping and screen-translating means, the view being taken on line 6—6 of Fig. 1.

Fig. 7 is a fragmentary sectional elevation of the screen-clamping mechanism taken on line 7—7 of Fig. 6, the clamping mechanism being shown in the released position it assumes when the screen is entering or being withdrawn from the mill housing.

Fig. 8 is a fragmentary plan view showing how the upper end of one of the screens is attached to the screen-translating chains.

Fig. 9 is a side view of the chain and attachment shown in Fig. 8.

Fig. 10 is a fragmentary sectional view taken on line 10—10 of Fig. 8.

Fig. 11 is an exploded isometric view showing details of the slipclutch driving mechanism employed in delivering power to the screen-clamping and screen-translating mechanisms.

Fig. 12 is a side elevational view showing in assembly the tracks and sprocket wheels employed in guiding the several screen-translating chains on one side of the mill housing.

Fig. 13 is an enlarged detailed sectional elevation of the track assembly taken on line 13—13 of Fig. 12.

Fig. 14 is an enlarged sectional elevation of the track assembly taken on line 14—14 of Fig. 12.

Fig. 15 is an enlarged sectional elevation taken on line 15—15 of Fig. 12 showing the chain tighteners.

Fig. 16 is a fragmentary enlargement of one of the track plates shown in Fig. 14 with the addition of a screen-translating chain mounted thereon.

Fig. 17 is a vertical sectional view taken on line 17—17 of Fig. 3 showing the solenoids associated with the screen-restraining latches.

Fig. 18 is an electrical wiring diagram showing remote controls applied to motor that operates the screen-changing mechanism.

45 Description of hammer-grinding mill and auxiliary equipment

Referring to Fig. 1, the grinding mill unit includes in general a crusher-feeder assembly 10 that receives whole ear corn or other unground materials, a hammer type grinding mill assembly 11 that receives the pre-crushed ear corn or materials from the crusher-feeder 10, and a motor-driven fan assembly 12 that withdraws the reduced material from the grinding mill and elevates it through pipe 13 to a dust collector (not shown). The crusher-feeder 10, which is driven

by V-belts 14 from motor 15, reduces the unground materials, such as ear corn, to a particle size that promotes accurate flow regulation to the grinding mill, the rate of flow being regulated by turning handle 16 on vertical stem 17, which stem projects a convenient distance above the operating floor. The lower end 18 of stem 17 is attached to the crusher-feeder flow control mechanism at 19 (Fig. 2). The material fed to the mill is ground in usual manner by impact of hammers 20 (Fig. 3) which are hinged to pivot bars 21 carried by radial arms 22 mounted upon shaft 23 for rotation therewith. The mill shaft 23, connected to a 3,600 R. P. M. motor (not shown), is journaled in a pair of bearings 24 (Fig. 1) attached to vertical side walls 25 of the lower section of the mill housing. The side walls 25 are tied together below the crusher-feeder by an inclined bottom plate 26 (Fig. 3) which delivers the flow of unground materials to the grinding chamber through the inlet opening 27.

With further reference to Fig. 3, the removable cover section 28 over the grinding chamber comprises a pair of semi-circular side walls 29, the periphery of which is welded to arcuate plate 30. The walls 29 are aligned vertically above side walls 25 of the bottom section of the mill housing, the upper and lower sections having flanges 31 and 32 respectively (Fig. 1) that are clamped together on parting line 33 to provide dust-tight construction around the hammer rotative element. The lowermost end 34 of arcuate plate 30 (Fig. 3) extends below the parting line 33 and is welded to cross bar 35 which bar is removably secured between side walls 25 of the lower section of the housing.

Underlying the hammer rotative element in the periphery of the grinding chamber is a rectangular opening 36 for the efflux of ground material, which opening is defined by two arcuate ribs 37 welded to side walls 25, the lower edge 38 of crossbar 35, and the lower edge 39 of inclined receiving plate 26. Removably clamped over the border elements that define the opening 36 is an arcuate working screen 40 through which the reduced product is graded as it escapes from the grinding chamber, this screen being held in working relation with the hammer rotative element by a clamping mechanism that will be subsequently described. The working screen 40 is subject to automatic removal and replacement by any one of the three similar idle screens 41, 42 and 43 shown stacked in layer formation above cover section 28 of the mill housing. Likewise, regardless of which screen is in the mill at the beginning of the screen interchange cycle, any one of the three other idle screens may be selected for direct interchange therewith.

The compartment 44, Figs. 3 and 6, which receives the efflux of ground material that is graded through the working screen, has an inclined bottom plate 45 (Figs. 1 and 3) which joins with the side walls 25 to form a gradually increasing U-shaped trough 46 (Fig. 6) which connects with the circular outlet opening 47 in the vertical cross wall 48 of the housing, the opposite end 49 of plate 45 being flanged upwardly to join with receiving plate 26. From opening 47 the reduced material travels through the tubular element 50 (Fig. 1) to inlet of fan 12. The top of the efflux-receiving compartment 44 is covered by plate 51 (Fig. 3) that is flanged upward at 52 to provide an open passageway 53 through which any screen may be translated into or out of compartment 44. This passageway is made dust tight, while the

working screen is held in operative relation with the hammer rotative element, by a closure that operates automatically in timed relation with the screen-translating mechanism, as will be subsequently described.

The several idle screens stored above the mill housing (Fig. 3) have their distal ends hanging downwardly into the passageway 53 in loose layer formation, so that any screen may be lowered into the mill housing or withdrawn therefrom without undue friction between abutting screen surfaces. Also, it will be seen that the proximal end 54 of working screen 40, and likewise any screen that may be introduced into the mill housing, projects above the distal ends of the idle screens. This overlapping relation of the working screen with respect to the idle screens makes it practical to move any screen upwardly or downwardly, within fixed limits, without danger of the ends of the screens fouling with each other.

Screen-clamping mechanism

As shown in Fig. 3 the working screen 40, or any screen interchanged therewith, is removably held over the outlet opening 36 and against stationary ribs 37, cross bar 35, and the lower end of receiving plate 26 by means of a power-operated toggle-clamping mechanism, which is further illustrated in Fig. 7 with the screen removed. This clamping mechanism includes three vertical arcuate clamping bars 55 which are formed concentrically with respect to stationary ribs 37, their lower ends 56 being hinged to pivot bar 57 supported by side walls 25 of the housing, while the upper ends are welded to cross header 58 to form a three-legged frame (Fig. 6) that may be swung inwardly to clamp the positioned screen to the border elements that define the peripheral screen opening 36; and contrawise, as shown in Fig. 7, this three-legged frame may be swung outwardly to release the screen for removal and interchange. The horizontal header 58, as best shown in Fig. 3, is angular in cross section, the inclined leg 59 being formed with a lower marginal edge that bears upon the outer face of the screen on a line that is directly opposite cross bar 35, thereby forming a dust-tight joint between screen and elements 59 and 35 in contact therewith. The upper marginal edge of vertical leg 60 of header 58 seats against resilient rubber gasket 61, which gasket is secured to underside of cover plate 51, thereby providing a dust-tight closure for screen passageway 53 when the screen is clamped in working relation with the hammer rotative element. Also, it will be seen that the closing and likewise the opening of passageway 53 takes place simultaneously with respect to the clamping and releasing of the screen.

The toggle mechanism (Figs. 3 and 6) that automatically clamps and releases the working screen is actuated by shaft 62 which has its ends journaled in side walls 25, the near end projecting beyond the wall to receive power-driven means that rocks the shaft to and fro through an angle of approximately 30° as will be described. Upon shaft 62 is mounted a tubular sleeve 63 secured thereto by pin 64 or other means, this sleeve having three upwardly projecting arms 65 that are aligned to engage and support cross shaft 66 which swings therewith when shaft 62 is moved. In pivotal engagement with shaft 66 are three plain links 67 that have their upper ends pivotally engaged to cross shaft 68 which is movable therewith. The linkage which operates the screen-

clamping elements further includes three bellcranks 69, details of which are shown in Figs. 4 and 5. The outer end of each bellcrank has an opening 70 which pivotally engages shaft 68, and an opening 71 on the opposite end which pivotally engages shaft 72 carried by clamping bars 55 (Fig. 7). Formed integral with each bellcrank 69 is an upwardly projecting ear 73 which has an opening 74 that receives the body of capscrew 75 in loosely fitting relation as best shown in Fig. 7, the threaded end of the capscrew being adjustably screwed into the threaded opening 76 of boss 77 on leg 59 of header 58. To make the clamping mechanism effective when closed upon screens of different thicknesses, a coiled compression spring 78 is assembled over capscrew 75, the lower end of the spring seating against ear 73 of the bellcrank, and the upper end against boss 77. The compressive strength of spring 78 determines the amount of clamping pressure applied to the screen when shaft 62 is turned counter-clockwise to swing pivotal shaft 66 into the plane with shafts 62 and 68 as in Fig. 3. In this position the linkage becomes locked and the screen is securely held against stationary ribs 37 until shaft 62 is subsequently turned in a clockwise direction. When capscrew 75 is properly adjusted, so that its head is spaced a short distance apart from the lower side of bellcrank ear 73, as indicated at 79 in Fig. 3, then spring 78 automatically compensates for any variation in thickness of the several screens employed in the mill. In addition, spring 78 effects a sudden snap-action release of the screen when the shaft 62 is turned clockwise a few degrees. After the screen is released, the head of capscrew 75 bears against the lower face of ear 73 of bellcrank 69, as may be seen in Fig. 7. When the screen is fully released, clamping bars 55 are swung outwardly away from ribs 37 to form the open space 80 therebetween, this space being relatively wide at the top and narrow at the bottom. The outward swing of clamping bars 55 is limited by making contact at 81 with sleeve 63 on shaft 62. Upon the projecting end of shaft 62 is mounted the bifurcated arm 82 (Fig. 1), which arm is made integral with hub 83 this hub being pinned at 84 (Fig. 6) to shaft 62, so that when arm 82 is tilted downward, as shown in Fig. 1, the screen-clamping mechanism is closed. Contrawise, when arm 82 is tilted upward, as shown in dot and dash lines, the screen is released for removal from the mill. The means employed to tilt arm 82 up and down through an angle of about 30° will be subsequently described.

Slipclutch mechanisms

Referring to Figs. 1, 2 and 11, the power that drives the screen-clamping mechanism, and likewise the screen translating mechanism, is obtained from shaft 85 which is journaled in bearings 86 mounted upon cover section 28 of the grinding chamber. Shaft 85 is driven by the reversible three-phase motor 87 which is mounted within the mill housing as shown by broken lines in Fig. 1. The power from motor 87 is transmitted to shaft 85 by any suitable speed-reducing means, the mechanism illustrated including countershaft 88 upon which is mounted sheave 89 driven from sheave 90 on the motor by V-belts 91, the countershaft being supported by the mill housing in any suitable manner. From sprocket 92 on countershaft 88 the power is transmitted by chain belt 93 to the relatively large sprocket 94 mounted on end section 95 of shaft 85. The

hub 96 of sprocket 94 is bored for axial slip fit on shaft 85, the shaft being driven by a feather key (not shown) that engages the keyway 97 (Fig. 11) in the shaft. Also, bored for slip fit and mounted on end section 95 of the shaft (Fig. 2) is a series of five smaller sprockets 98 to 102 which drive chains 103 to 107 respectively; the chain 103 being belted to a relatively large sprocket 108 which operates the screen-clamping mechanism and also serves as a rotative timing element for the electrical controls as will be explained. On the opposite end section 109 of shaft 85 are mounted four sprockets 110 to 113 that are duplicates of sprockets 99 to 102 on opposite end of shaft, and to sprockets 110 to 113 are belted chains 114 to 117 respectively. The chains 104—114, 105—115, 106—116 and 107—117 are paired to travel in unison and are employed for translating the screens 40 to 43 respectively into and out of the mill, as will be further explained.

To each of the driving sprockets mounted on shaft 85 is applied an individual slipclutch mechanism that transmits a predetermined amount of torque before slippage takes place, this torque being the same for all of the sprockets. With shaft 85 turning in either direction, the paired sprockets associated with any screen slip in unison when the screen is standing still, and under certain conditions all of the clutch mechanisms may slip simultaneously. Inasmuch as the several clutch mechanisms are all identical in construction and operation, only one will be described, and for the purpose of illustration the one applied to sprocket 110 has been selected. The slipclutch mechanism that drives sprocket 110, Fig. 11, includes a pair of fiber friction disks 118 bored for running fit on shaft 85; and a pair of metal disks 119, each of which is formed with bore 120 having an inwardly projecting spline 121 which slidably engages keyway 97 in the shaft, so that the disk rotates with the shaft regardless of its axial position thereon. These disks are assembled on the shaft in symmetrical relation with respect to sprocket 110, the fiber disk being sandwiched between the metal disk and sprocket and in frictional contact with both, so that when the assembly is subjected to axial thrust from opposite directions, the sprocket is caused to rotate with the shaft. The amount of torque delivered by the sprocket to the chain thereon, before slippage takes place, depends upon the amount of axial pressure applied to the assembly.

With further reference to Fig. 11, the nut 122 in engagement with threaded end 109 of shaft 85 provides a convenient means for regulating the amount of axial thrust that is simultaneously applied to the several slipclutch mechanisms assembled in multiple upon the end section of the shaft. The nut 122 seals against auxiliary metal disk 123, which disk is bored for slip fit on the shaft and held in spaced relation from the outermost metal disk 119 by three or more coiled compression springs 124, these springs being held in place by assembling one end over suitable inwardly projecting bosses 125 carried by end disk 123. Thrust collar 126 (Fig. 2) takes the reaction of nut 122 on end section 95 of shaft 85. The sprocket disk 94 on end section 95 of the shaft serves the same purpose as disk 123 on the opposite end section, and disk 94 is held in spaced relation from adjacent splined disk 119 by coiled springs 124 in the same manner, so that when nut 127 is adjusted to bear against hub 96 of sprocket 94, the multiple slipclutch mechanisms are subjected to the necessary axial thrust in same man-

ner as applied to the slipclutch mechanisms mounted on opposite end section of shaft.

Screen-translating mechanisms

To the proximal end of each of the four screens is attached a horizontal drawbar 128, Figs. 8 and 10, which projects beyond sides of the screen to engage translating chains associated therewith. Drawbar 128 is attached to screen 40 by means of centrally disposed hinge butts 129 and 130 welded to the drawbar and screen respectively, the butts being detachably secured together by removable pivot pin 131. Translating chains 104 and 114 associated with screen 40 each carry an attachment 132 which is formed with a rectangular opening 133 as shown in Fig. 9, this opening being adapted to receive the end of drawbar 128 in loosely fitting relation, so that when the paired chains travel in unison the screen is moved therewith. Consequently, the screen is translated into the mill housing when the chains travel in a clockwise direction, and contrawise, from the housing when the travel is counterclockwise. In like manner screens 41, 42 and 43 are translated by paired chains 105—115, 106—116 and 107—117 respectively. The downward travel of the screens is limited by a pair of vertical stops 134—134 (Fig. 3) upon which the drawbar 128 comes to rest when the screen is positioned within the mill ready for clamping. These stops also form the opposite end walls of screen passageway 53. The upward travel of the screens is also limited by the drawbars coming to rest against vertical stop plates 135—135, which plates are welded to cover section 28 of the mill housing. After the screen has reached the limit of its travel in either direction, the slipclutch mechanism associated therewith must slip until shaft 85 comes to a standstill.

Screen-restraining mechanisms

When shaft 85 rotates in a clockwise direction the idle screens are all urged by their respective slipclutch mechanisms to move downward into the mill housing. As only the selected screen may be allowed to move downward into the mill, it becomes necessary to apply individual restraining means to each of the several screens, this means being subject to solenoidal release as will be explained. The restraining means (Figs. 3, 8 and 17) comprises spring-urged latches 136 to 139 for screens 40 to 43 respectively. To the upper edge of each draw bar 128 is welded a flat centrally disposed ear 140 that has an elongated opening 141 which is adapted to engage the restraining latch associated with the screen. As the latches are all similar in construction and operation, only latch 136 (Fig. 3) will be described in detail, this latch being formed as a bellcrank with body welded to cross shaft 142 which has opposite ends pivotally mounted in vertical stop plates 135 so that the latch may be tilted in a vertical plane. The upper end 143 of the latch is formed as a pointed hook that engages opening 141 in drawbar ear 140 when drawbar 128 is positioned against stop plates 135. The pointed hook 143 is urged downward into opening 141 by action of coiled spring 144, this spring being tensioned between arm 145 of the latch and cover plate 146 which spans stop plates 135. Thus engaged by latch 136, screen 40 is securely restrained from downward movement into the mill while shaft 85 is rotating in clockwise direction. The means employed to free the screen from the latch includes vertical pushrod 147 which is operated by a solenoid, as will be further explained, the lower

end of this pushrod being pivotally attached to the outer end of arm 145 of the latch, so that when the latch is tilted counterclockwise the hook 143 is raised to clear drawbar ear 140. In this manner similar pushrods (Fig. 17) 148, 149 and 150 are employed to actuate latches 137, 138 and 139 respectively.

Solenoidal release of selected screen

Referring more especially to Figs. 3 and 17, it will be seen that latches 136 to 139 are operated by individual solenoids 151 to 154 attached to vertical pushrods 147 to 150 respectively. These are conventional solenoids with an iron plunger that moves downward when energized. They are mounted upon plate 146 which is provided with an opening (not shown) below each solenoid through which the plungers connect with the vertical pushrods. Only one of the solenoids may be energized at a time, and this solenoid remains energized until the bifurcated arm 82 is tilted downward to clamp the positioned screen in operative relation with the hammer rotative element. After the solenoid is deenergized, the spring-urged latch tilts clockwise to resume its normal position in readiness to engage the screen associated therewith when the screen is withdrawn from the mill. The electrical circuits and the timing mechanism employed in energizing the four solenoids will be subsequently described in connection with the wiring diagram shown in Fig. 18.

Tracks for screen-translating chains

To translate the screens up and down through the screen passageway 53 without flexing, and to avoid undue friction with each other and stationary parts of the mill housing, it becomes necessary to guide the proximal end of each screen and the drawbar connected thereto over a fixed path, this path approximating the arc of a circle having its center located within the confines of the grinding chamber. This is accomplished by providing a curved or arcuate track for each of the screen translating chains to travel upon, the several tracks being generally designed as assemblies 155 and 156 which are rigidly attached to opposite side walls of cover section 28 of the mill housing as shown in Figs. 1, 2, 6, 12, 13 and 14. The assembly 155, which is mounted on near side of mill, includes spaced-apart track plates 157 to 160, the upper marginal edges of these plates serving as tracks for chains 104 to 107 respectively. Likewise, assembly 156 includes track plates 161 to 164 for chains 114 to 117 respectively. Referring more especially to Figs. 12, 13 and 14, the lower ends of the curved track plates are supported in common on stud 165 welded to adjacent wall plate of cover section. With stud 165 as a pivotal point, the upper sections of the several track plates in each assembly are fanned out in fixed overlapping relation, so that the upper marginal edges of paired plates 160—164, 159—163, 158—162 and 157—161 are positioned at progressively higher levels in the order related. This arrangement of the track plates provides working clearance between the several drawbars 128 when they are stacked above the cover section. This clearance decreases as the arcuate tracks approach a common point of tangency directly over the screen passageway 53 (Fig. 3). In other words, regardless of which screen is in the mill, its drawbar will be positioned in common as shown in dot and dash lines 166, Fig. 12.

As illustrated in Figs. 12 and 16, the screen-translating chains are conventional roller chains with rollers 167 tied together by paired links 168-168 and 169-169, the lower extremities of inside links 168 overlapping the rollers and straddling the track plate such as 157, thereby guiding the travel of the chain thereon. To further increase the stability of the chains traveling over the arcuate tracks, the periphery of each track plate, such as 157, is made with a plurality of circumferentially spaced C-shaped indentations 170 into each of which is assembled a small sprocket 171 that is positioned so that its uppermost teeth engage the chain traveling on the track plate. As best shown in Fig. 13, each sprocket is rotatively mounted on a shouldered stud 172 riveted to ear 173 which ear is welded to the track plate. The lower end of track plate 157 is welded to ear 174 (Fig. 12) which engages stud 165, thereby providing supporting means for the lower end of the plate. Also, mounted upon stud 165 for rotation thereon and aligned with plate 157 is an idler sprocket 175 that is similar to sprocket 171 and which serves the same purpose. Likewise, track plates 158, 159 and 169 are provided with idler sprockets 171 and 175. The track assembly 156 is a duplicate of assembly 155 in all respects except it is mounted upon the opposite side of cover section 28 in opposite hand relation, so that fanned-out ends of track plates 160-154, 159-163, 158-162 and 157-161 are paired to support the chains mounted thereon at progressively higher levels.

To provide means for individually tensioning each of the screen-translating chains, such as chain 104, the lower span of the chain is carried over idler sprocket 176 as shown in Figs. 12 and 15, the sprocket being rotatably supported upon stud 177 riveted to plunger element 178, the plunger being slidably mounted for vertical adjustment within the boxlike housing 179 attached to the adjacent side wall of mill. The plunger is raised to tension chain 104 by adjusting setscrew 180 threaded into bottom 181 of housing 179, the upper end of the setscrew bearing against the lower end of the plunger. The chains 105, 106 and 107 are tensioned in the same manner, the several plungers associated therewith being assembled in housing 179. Chains 114 to 117 on opposite side of mill are tensioned in the same manner.

Timing mechanism for screens

It will now be recalled that when shaft 62, Fig. 3, is rocked in a clockwise direction by tilting bifurcated arm 82 upward about 30°, the working screen is released from the clamping mechanism, and contrawise, when the arm is tilted downward the screen is clamped against arcuate ribs 37. The arm 82 (Fig. 1) is tilted up and down by power obtained from the slipclutch mechanism applied to sprocket 98 on shaft 85, the chain belt 103 delivering power therefrom to timing sprocket 108 as previously explained. Sprocket 108 is rotatively mounted upon stud shaft 182 which is supported by near side wall of the mill. This sprocket 108 carries an inwardly projecting crankpin 183 that tilts arm 82 up and down, the travel of the crankpin being about 315° back and forth on circular arc shown by dot and dash line 184. The crankpin 183 is shown in cross section as a result of a fragment of sprocket 108 being deleted. While the crankpin is moving upward in counterclockwise direction, the working screen is released from the

clamping mechanism by snap action as previously explained, and the screen instantly starts its upward journey out of the mill as a result of the torque-responsive slipclutch mechanism associated with the screen chains. Reversing motor 87 for clockwise rotation, and likewise crankpin 183 carried by timing sprocket 108, instantly starts the pre-selected idle screen on its journey into the mill, it having been previously released from its restraining latch by the solenoid associated therewith when the working screen was released from its clamping mechanism at the beginning of the screen interchange cycle. The selected screen is released from its tilting latch while shaft 85 is turning counter-clockwise, under which condition there is no strain on the latch as the reserve screens are being urged upward by the slipclutches associated therewith. The crankpin 183 is limited in its travel in both directions by electrical controls applied to motor 87 which will be presently described.

The bifurcated arm 82 (Fig. 1) is formed with upper and lower forks 185 and 186 respectively, these forks being spaced apart vertically in parallel relation a distance that is approximately two to three times the diameter of crankpin 183. The upper fork is made shorter than the lower fork, and the distal end of the lower fork is turned upward to provide finger 187 which serves as a positive stop against which the crankpin comes to rest at the end of its clockwise movement, this also being the end of the screen interchange cycle. When the crankpin seats against finger 187, the bifurcated arm 82 is tilted to its lowermost position, and the working screen is clamped ready for service. The open space 188 between finger 187 and the end of upper fork 185 provides a gap through which the crankpin, when traveling counterclockwise, escapes from the confines of the two forks, the arm 82 being tilted to its uppermost position as shown by dot and dash lines. Continuing its counterclockwise travel, the crankpin engages a spring-loaded arm 189 which actuates single pole double-throw limit switch 190 secured to near side wall of the mill housing, its arm 189 being normally positioned to maintain motor 87 energized for counterclockwise rotation by means of holding coil 191 of Fig. 18. Holding coil 191 is released and opposite holding coil 192 is energized when arm 189 is engaged by the crankpin, thereby reversing the motor for clockwise rotation, and likewise shaft 85 and the crankpin 183. The reversal of shaft 85 instantly starts the previously released screen on its downward journey into the mill. Holding coil 192 continues to function until the end of the cycle, however, arm 189 of limit switch 190 returns to its normal position as soon as the crankpin has traveled a few degrees in clockwise direction. In its clockwise travel the crankpin re-enters gap 188 and tilts the bifurcated arm downward, thereby closing the clamping mechanism upon the interchanged screen. The time interval involved in the screen clamping operation is relatively long as compared with that required to release the screen, which, as will be recalled, is a sudden snap action. This sudden release of the screen speeds up its removal from the mill.

With further reference to Figs. 1 and 18, before crankpin 183 reaches the limit of its clockwise travel, and likewise before bifurcated arm 82 is tilted to its lowermost position, the lower edge of the bifurcated arm engages the spring-loaded arm 193 of single-pole double-throw limit switch 194, which switch is also mounted on near side

of mill housing. The engagement of arm 82 with switch arm 193 releases holding coil 192 and interrupts the current to motor 87. After the motor is de-energized it continues to coast until the crankpin stops against finger 187 of the bifurcated arm. During this brief coasting period the slip-clutch mechanism applied to sprockets 98 to 192 and 110 to 113 on shaft 85 are all slipping. The solenoid associated with the screen now in the mill was simultaneously de-energized when holding coil 192 was released to stop the motor. The electrical circuits employed in controlling the motor, solenoids, and the pilot lights will be presently described in detail.

Pushbutton controls and signal lights

Referring to the wiring diagram, Fig. 18, the three-phase motor 87 is operated from line wires 195, 196 and 197, and is energized for counterclockwise rotation at the beginning of each screen interchange cycle by manually pressing any one of the four spring loaded pushbuttons 198, 199, 200 or 201 that is not in a depressed position, these pushbuttons being associated with screens 40, 41, 42 and 43 respectively. Each pushbutton operates a normally open double 2-point-make selecting switch that closes two circuits simultaneously, one of these circuits lighting a signal lamp associated with the idle screen that has been selected for interchange with the working screen in the mill. The other circuit energizes the solenoid that releases the restraining latch that is associated with the selected screen. When the operator presses any one of pushbuttons 198, 199, 200 and 201, this simultaneously closes contacts 202 and 203, 204 and 205, 206 and 207, or 208 and 209 respectively. The contacts 202, 204, 206 and 208 are in the circuits that energize pilot lamps 210, 211, 212 and 213, which lamps are associated with screens 40, 41, 42 and 43 respectively. The contacts 203, 205, 207 and 209 are in the circuits that energize solenoids 151, 152, 153 and 154 respectively, these solenoids being associated with screens 40, 41, 42 and 43 as previously mentioned. When motor 87 is at rest the current from line wire 195 flows through single-pole double-throw limit switch 194 as a result of its spring-loaded arm 193 being engaged with bifurcated arm 82, thereby holding blade 214 against terminal 215 from which the current flows through the signal lamp associated with the screen that is in the mill, and thence the current flows to line wire 197 to complete the circuit.

Mechanically connecting the four pushbutton switches 198, 199, 200 and 201 in common is a normally open switch blade 216 which is hinged on terminal 217 so that it may be momentarily closed against terminal 218 when the operator presses any pushbutton associated with an idle screen. These pushbuttons are so arranged and interlocked that when the selected pushbutton is pressed, it first releases any other pushbutton that may be in a depressed position as a result of the prior screen interchange, and then the selected pushbutton locks itself mechanically in the depressed position until subsequently released by the operator when he presses one of the other pushbuttons to effect another screen interchange. The signal lamp associated with the ex-working screen is extinguished when the depressed pushbutton is released, and simultaneously the signal lamp associated with the selected screen is energized as a result of the operator pressing the selected pushbutton. However, this lamp is lighted for only an instant, or until motor 87 has

turned a few counterclockwise revolutions to raise crankpin 183 and free bifurcated arm 82, which arm now swings upward with a snap action. This upward movement of arm 82 frees arm 193 of limit switch 194, the current to the lamp being interrupted when blade 214 leaves terminal 215. This same lamp circuit is again energized at the end of the screen interchange cycle, as will be later described.

10

Motor starting and reversing controls

The only manual operation required to make the screen interchange is for the operator to press the pushbutton associated with the selected idle screen that is to be put into the mill. The pressing of this pushbutton momentarily closes the switch blade 216 against terminal 218 and energizes holding coil 191, the flow of the current being from line wire 195 through closed switch 216, contacts 219 which are operated by heater coils 220 and 221 to provide overload protection for motor 87, thence through safety switch 222, closed switch 216, terminal 217, holding coil 191, limit switch 190, and then to line wire 197 to complete the circuit. The energizing of holding coil 191 magnetically closes the four ganged contacts 223, 224, 225 and 226 simultaneously. The closing of contacts 223 shunts the current around switch 216 and keeps holding coil 191 energized after switch blade 216 has resumed its normally open position. The closing of contacts 224, 225 and 226 delivers current to motor 87 from line wires 195, 196 and 197, and the motor starts in a counterclockwise direction, the crankpin 183 being driven in the same direction. After the motor has turned a few revolutions and crankpin 183 has traveled upward a short distance, the bifurcated arm 82 swings upward with a snap action as previously explained, thereby releasing the spring-loaded arm 193 of limit switch 194 and swinging blade 214 to terminal 221. This completes the solenoid circuit from line wire 195 through limit switch 194 and the closed pushbutton contacts to line wire 197, the solenoid associated with the selected screen now being energized and the screen freed from its restraining latch. Simultaneously, when blade 214 contacts terminal 221, the wire leading therefrom to holding coil 192 becomes ready to function, and holding coil 192 is energized the instant the circuit is completed through limit switch 190, as will be presently described.

After leaving the bifurcated arm 82 the crankpin continues its counterclockwise travel until it engages the spring-loaded arm 189 of limit switch 190, during which time interval the ex-working screen is withdrawn from the mill. When blade 228 leaves terminal 229 in limit switch 190, this de-energizes holding coil 191, and, when the blade swings over to terminal 230, this completes the circuit that energizes holding coil 192. The de-energization of holding coil 191 releases the four ganged contacts 223, 224, 225 and 226, and the motor stops with the crankpin in engagement with arm 189 on limit switch 190. The energizing of holding coil 192 magnetically closes ganged contacts 231, 232, 233 and 234 simultaneously. The closing of contacts 231, 232 and 233 permits the current from line wires 195, 196 and 197 to flow through the motor in reverse phase relation, thereby energizing the motor for clockwise rotation. The closing of contacts 234 shunts the current around limit switch 190 so that holding coil 192 remains energized. After crankpin 183 has traveled upward a short distance, and has

disengaged spring-loaded arm 189 of limit switch 190, the switch blade 228 returns to its normal position in contact with terminal 229. The motor continues to rotate in clockwise direction until crankpin 183 re-engages bifurcated arm 82 and tilts it downward to re-engage arm 193 of limit switch 194, the blade 214 swinging away from terminal 227 thereby simultaneously interrupting the flow of current through holding coil 192 and the solenoid which was energized at the beginning of the screen interchange. The de-energization of holding coil 192 permits ganged contacts 231, 232, 233 and 234 to open and de-energize the motor, this action taking place a brief interval of time before crankpin 183 comes to rest against finger 187 on the bifurcated arm. The motor continues to coast until the friction of the slipping clutches on shaft 25 brings it to a standstill.

Example illustrating screen interchange cycle

Any one of the four screens that may be in the mill and clamped ready for service is subject to replacement by any one of the other three screens by simply pressing the pushbutton associated with the selected idle screen. Therefore, the electrical controls illustrated in wiring diagram, Fig. 18, must be designed to effect a total of twelve screen-interchange combinations, all of which operate on the same basic cycle. Consequently, it will be necessary to describe in detail only one screen interchange, and for this purpose idle screen 42 has been selected for introduction into the mill to replace working screen 40 which is now clamped in operative relation with the hammer rotative element as shown in Fig. 3. As a result of the preceding screen interchange, pushbutton 198 is in a depressed position and the entire electrical control system is at rest with the exception of signal lamp 210 which is lighted to indicate that screen 40 is in the mill. The current for lamp 210 flows from line wire 195 through junction 235, lead 236, overload protection contacts 219, safety switch 222, lead 237 to junction 238 thence through lead 239 to limit switch 194 which has its spring-loaded blade 214 closed against terminal 215. From terminal 215 lead 240 conducts the current to pushbutton make-contacts 202, through lamp 210, lead 241, thence to junction 242 with line wire 197, thereby completing the circuit for lamp 210 which remains lighted as long as pushbutton 198 is depressed.

To start the screen interchange cycle, whereby working screen 40 now in the mill is replaced by selected screen 42, the operator simply presses pushbutton 200, thereby simultaneously releasing depressed pushbutton 198 and momentarily closing switch 216 against contact 218. As pushbutton 200 remains in a depressed position, the two-point make-contacts 206 and 207 are closed and remain closed until the next screen interchange. While switch 216 is momentarily closed against terminal 218 the current from line wire 195 is carried through junction 235 with lead wire 236, normally closed switches 219 and 222, lead 237 through switch 216, lead 243, holding coil 191, lead 244 to terminal 229 of limit switch 190 against which blade 228 is normally closed, thence through lead 245 to junction 246 to line wire 197, thereby completing the circuit between lines 195 and 197 which energizes holding coil 191 and magnetically closes the four ganged contacts 223, 224, 225 and 226.

When contacts 223 are closed this shunts out the momentary contact 216, so that when switch 216 is again opened, the holding coil 191 will remain energized to maintain ganged contacts 223, 224, 225 and 226 closed. As soon as these four contacts are closed, the three-phase current from lines 195, 196 and 197 flows through contacts 224, 225 and 226 respectively. From contact 224 the current flows through lead 247 to heater coil 220, and then through lead 248 to motor 87. From contacts 225 the lead 249 goes to the motor. From contacts 226 the lead 250 goes to heater coil 221 from which the current goes to motor through lead 251. This completes the three circuits to the motor which is now energized for counterclockwise rotation.

It will now be recalled that crankpin 183 (Fig. 1) carried by sprocket 103 rotates in same direction as motor 87, consequently, the crankpin 20 starts traveling counterclockwise when holding coil 191 is energized at the beginning of the screen interchange cycle, thereby tilting the bifurcated arm 82 upwardly to release the screen-clamping mechanism that holds screen 40, which screen 25 starts its upward journey as soon as freed from the clamping mechanism. In addition, when arm 82 is tilted upwardly it frees the spring-loaded arm 193 of limit switch 194 so that blade 214 is moved to contact terminal 227, which, through lead 252, conducts the flow to contacts 207 of pushbutton 200, these contacts being mechanically maintained in closed position, as previously explained, so that the current may flow through lead 253 to solenoid 153 associated with screen 42. From solenoid 153 the current is carried through wire 245 to junction 246 and line wire 197 to complete the circuit, thereby energizing solenoid 153 which lifts the restraining latch 138 and releases screen 42 which is now free to start its downward journey into the mill housing at the instant the motor is reversed for clockwise rotation. The crankpin 183, continuing its counterclockwise travel, engages arm 189 of limit switch 190, during which time interval screen 40 is completely withdrawn from the mill housing and positioned so that ear 149 on drawbar 128 engages the spring-urged restraining latch 136. Engagement of the crankpin with arm 189 of the switch 190 swings blade 228 from contact 229 to contact 230. When blade 228 leaves contact 229, the circuit through holding coil 191 is broken, thereby releasing contacts 223, 224, 225 and 226 and disconnecting motor 87 from its source of energy.

With blade 228 of limit switch 190 in contact with terminal 230, as mentioned in preceding paragraph, motor 87 is again energized, this time the direction of rotation being reversed or clockwise. The reversal is effected by current from line wire 195 flowing through branch 236, normally closed switches 219 and 222, lead 237, junction 238, branch 239 thence to limit switch 194 having blade 214 normally held in contact with terminal 227, then through lead 252 to junction 254 and lead 255 to holding coil 192, lead 256 to limit switch 190 having blade 228 in contact with terminal 230 as a result of engagement of crankpin 183 with arm 189. From blade 228 the current flows through lead 245 to junction 246 with line wire 197, thus completing the circuit between lines 195 and 197, and thereby energizing holding coil 192 which magnetically closes the four ganged contacts 231, 232, 233 and 234. With contact 234 closed, the current flowing through holding coil 192 is shunted across

15

from wire 256 to junction 242 with line wire 197, thereby maintaining holding coil 192 energized after blade 228 of limit switch 198 has been moved from contact with terminal 230 to engage terminal 229, which action takes place as soon as crankpin 183 disengages the spring-urged arm 189 of switch 198.

With contacts 231, 232, 233 and 234 closed by action of holding coil 192 the three-phase current is carried from line wire 195 to junction 257, through lead 258, closed contacts 231, lead 259 to junction with 250, thence through heater coil 221 to motor 87. From line wire 196 the current flows through lead 260, closed contacts 232, lead 261 to junction with wire 249 which is connected to the motor. From line wire 197 the current flows through lead 262, closed contacts 233, lead 263 to junction with wire 247, and then through heater coil 220 to motor 87. Energizing these three circuits reverses the motor for rotation in a clockwise direction. Simultaneously crankpin 183 starts on its return journey in a clockwise direction and screen 42 starts its downward journey into the mill housing, it coming to rest when its drawbar 128 engages stops 134 (Fig. 3). Immediately following the arrival of screen 42 in position to be clamped for service, the crankpin, having re-entered gap 188 of the bifurcated arm, engages the lower fork 186 of the arm and starts tilting it downwardly, this action clamping screen 42 in operative relation with the hammer rotative element as previously described. Before arm 82 is tilted to its lowermost position, lower fork 186 engages arm 193 of limit switch 194 and swings blade 214 from terminal 227 to 215, thereby interrupting the current flowing through holding coil 192 and solenoid 153, and releasing contacts 231, 232, 233 and 234 which action simultaneously stops the motor and lights signal lamp 212 to indicate that screen 42 is clamped ready for grinding service. The circuit for signal light 212 is same as the circuit previously described for light 210 except the current flows through pushbutton contacts 206 instead of contacts 202, and light 212 remains lighted until screen 42 is withdrawn from the mill housing, or the circuit is interrupted by opening switch 222.

What I claim is:

1. In a hammer mill or the like including a housing, an arcuate screen which is one of a plurality of similar interchangeable screens removable from and insertable therein, means attached to the housing for supporting the screens exteriorly thereof, an opening in the housing through which a selected screen may be translated, a mechanism for closing the opening, a mechanism for translating the selected screen through the opening, and motor means for actuating said mechanisms in timed relation, said means including an oscillatable element.

2. In a hammer mill or the like including a housing, a screen which is one of a plurality of interchangeable grading screens removable from and insertable therein, an automatic mechanism for removing any screen of the plurality that may be in the housing and inserting a selected screen of the plurality in substitution therefor, said mechanism including a combination a pair of sprocket chains associated with each screen, a sprocket for driving each chain, a motor-driven reversible shaft upon which the said sprockets are mounted for rotation therewith or relative thereto, said sprockets also being mounted for axial movement relative to the shaft, and a

spring-urged frictional driving connection between the shaft and each sprocket.

3. The combination as cited in claim 2 wherein the maximum torque transmitted by the driving connection is varied by adjusting means carried by the shaft and rotatable therewith.

4. The combination as cited in claim 2 wherein the driving connections associated with the paired chains slip simultaneously.

5. The combination as cited in claim 2 wherein the driving connection includes a driving disk mounted on the shaft adjacent to the sprocket for positive rotation with the shaft and axial movement relative thereto, an intermediate disk mounted between the sprocket and the driving disk for rotational and axial movement relative to the shaft, and resilient means for forcing the driving disk and sprocket axially towards each other to cause said sprocket to rotate with the shaft.

6. In a hammer mill or the like including a housing, a screen which is one of a plurality of interchangeable screens insertable therein and removable therefrom, means associated with the housing for supporting the reserve screens thereabove in an established order, an opening in the periphery of the housing into which any selected screen may be inserted, a screen inserted in the opening, and means for maintaining the inserted screen in the established order with respect to the reserve screens thereabove, the said means being the distal ends of the reserve screens hanging loosely in overlapping relation with proximal end of the inserted screen.

7. In a hammer mill or the like including a housing, an arcuate screen which is one of a plurality of interchangeable metal screens insertable therein and removable therefrom, an opening in the housing through which any selected screen may be translated, a screen inserted in the housing, and means for supporting the reserve screens in loose-leaf formation with their proximal ends in spaced apart relation and their distal ends in metal-to-metal contact, said supporting means being the housing structure.

8. In a hammer mill or the like including a housing, a screen which is one of a plurality of interchangeable screens insertable therein and removable therefrom, an opening in the housing through which any selected screen may be translated, a reversible mechanism for translating the selected screen through the opening, said mechanism being operated by a motor, a source of electrical energy to the motor, an active screen inserted in the housing and the motor at rest, manually operated electrical controls for starting the motor in a predetermined direction to remove the inserted screen, and electrical contacts associated with the screen translating mechanism for automatically reversing the motor after removal of said screen.

9. The combination as set forth in claim 8 wherein the electrical controls include a normally closed spring-loaded limit switch, and means for opening the switch to automatically de-energizing the motor after completion of the screen interchange, said means including an oscillatable element which is actuated by said motor.

10. In a hammer mill or the like including a housing, a screen which is one of a plurality of interchangeable screens insertable therein and removable therefrom, an opening in the housing through which a selected screen may be translated, a reversible motor-driven mechanism

for removing the active screen and inserting the

selected screen, a source of energy to the motor, manually operated electrical controls for starting the motor to effect a screen interchange, said controls including a switch which closes two pair of contacts simultaneously, a signal lamp associated with each of the several screens, and means for energizing the lamp associated with the inserted screen while the balance of the electrical system is at rest, said means being one pair of the closed contacts.

11. In a grinding mill or the like including a housing, a rotative hammer element which reduces material fed thereto, a screen supported in operative relation with the rotative element, said screen being one of a plurality of similar screens interchangeable therewith and positionable upon the screen supports in like operative relation, a screen-translating mechanism for automatically removing the operative screen and positioning any selected screen of the plurality in substitution therefor and in like operative relation, a rotative element for timing the operations of the screen-translating mechanism, and reversible power-driven means in common for actuating the timing element and the screen-translating mechanism.

12. The combination as cited in claim 11 which includes torque-responsive means for establishing a driving connection between the power driven means and the screen translating mechanism, said means being a slipclutch.

13. In a hammer-grinding mill or the like including a housing into which is inserted an active screen through which the efflux of reduced material is graded, said screen being one of a plurality of similar screens interchangeable therewith and positionable in substitution therefor, means for supporting the reserve screens exteriorly of the housing, a reversible screen positioning mechanism for replacing the active screen by any selected reserve screen, power-operated means for actuating the screen positioning mechanism to effect the screen interchange, a source of electrical energy, and electrical controls associated with each of the several screens which may be manually operated to select the reserve screen prior to the interchange.

14. The combination as cited in claim 13 wherein the power operated means is an electric motor having reversing controls, said controls being actuated automatically by rotative means driven by the motor.

15. The combination as cited in claim 13 which includes a rotative timing element associated with the screen-positioning mechanism, a reversible electric motor for actuating the timing element and the positioning mechanism, a source of energy to the motor, and electrical means for controlling the direction of motor rotation, said means comprising a pair of spring-loaded single-pole double-throw limit switches which are actuated by the rotative timing element.

16. In a hammer-grinding mill or the like including a housing into which is inserted a screen through which the efflux of the reduced material is graded, said screen being one of a plurality of similar screens interchangeable therewith and positionable in substitution therefor, a motor-driven screen positioning mechanism for effecting an interchange of any selected reserve screen with the active screen, a source of energy to the motor, and electrical controls for the motor, said controls including a manually operated switch for selecting the reserve screen that is to interchange with the active screen, and means in common

with the manually operated switches for starting the motor, said means being a normally open switch.

17. The combination as cited in claim 16 wherein the screen-positioning mechanism includes a slip clutch and a solenoidally operated latch associated with each of the reserve screens, the said latches being adapted to hold the reserve screens immovable while the selected screen is being interchanged with the active screen, and means for energizing the solenoid to release the selected screen, said means being the manually operated switch.

18. In a hammer-grinding mill or the like including a housing, a screen which is one of a plurality of interchangeable grading screens insertable therein and removable therefrom, an opening in the housing through which any selected screen of the plurality may be inserted, a reversible mechanism for translating the selected screen into the housing, said mechanism including an oscillatable clamping element power driven means for actuating the said mechanism, a source of electrical energy, an electrically operated indicator associated with each of the several screens for visually indicating which one of the screens is inserted in the housing, said indicators being stationed remotely from the mill, an electrical circuit for each indicator, a switch in each indicator circuit, means for closing the switch associated with the selected screen, a master switch in common with all the indicator circuits, and means for operating the master switch, said means being the oscillatable clamping element.

19. In a hammer-grinding mill or the like including a housing into which is inserted an arcuate screen through which the efflux of reduced material is graded, said screen being one of a plurality of similar screens interchangeable therewith and positionable in substitution therefor, means carried by the housing for supporting the reserve screens thereabove in juxtaposed nested relation, an opening in the housing into which a selected screen may be inserted and removed, a reversible mechanism for removing the active screen from the housing and replacing it with any selected reserve screen in substitution therefor, and motor means for actuating the reversible mechanism.

20. In a hammer-grinding mill of the type that employs interchangeable grading screens, a housing having a grinding chamber in which is journaled a rotative hammer element for reducing material fed thereto, a compartment which receives the reduced efflux from the grinding chamber, an opening in the periphery of the grinding compartment which communicates with the efflux-receiving compartment, a screen removably positioned over the opening in overlapping relation with the border elements that define the opening, a reversible mechanism for clamping the positioned screen to the border elements and holding said screen in operative relation with the hammer element, and an electrically operated indicant remote from the mill for visually indicating when the positioned screen is clamped in operative relation with the hammer element.

21. In a hammer-grinding mill or the like including a housing into which is journaled a hammer rotative element for reducing material fed thereto, a screen inserted in the housing through which the efflux of reduced material is graded, said screen being one of a plurality of similar

reserve screens interchangeable therewith and positionable in substitution therefor, means for supporting the reserve screens, a reversible screen-positioning mechanism for replacing the operative screen by one of the reserve screens, and an electrically operated indicant remote from the mill for indicating which one of the several screens is positioned in operative relation with the hammer element.

22. In a hammer-grinding mill or the like including a housing into which is inserted a screen through which the efflux of ground material is graded, said screen being one of a plurality of similar screens interchangeable therewith and positionable in substitution therefor, a screen-positioning mechanism for effecting the screen interchange to selectively vary the fineness of the material in the efflux, an indicant associated with each screen which may be seen by the operator from a station elevated above the mill housing, a normally open electrical circuit for operating each indicant, a source of energy for each circuit, and means for automatically closing the circuit which is associated with the inserted screen.

23. The combination as set forth in claim 22 wherein the indicant associated with the inserted screen includes a lamp.

24. In a machine that employs a removable screen or the like, said screen being one of a plurality of similar screens interchangeable therewith and positionable in substitution therefor, the combination that includes a mechanism for translating each screen to effect an interchange of any reserve screen with the employed screen, a rotative shaft in common for actuating the screen translating mechanisms, a permanently engaged torque-responsive element for connecting each screen translating mechanism to the shaft, said elements being mounted on the shaft for rotation therewith or relative thereto, and means supported by the machine structure for restraining movement of the screens to cause a plurality of the torque-responsive elements to slip simultaneously.

25. In a hammer mill that employs arcuate grading screens, a housing, an opening in the housing into which a screen may be inserted, a screen supported above the housing by means attached to the mill structure, a reversible mechanism for inserting the screen into the opening, means for actuating the reversible mechanism, and pivotal means for connecting the screen to the said mechanism, said pivotal means being detachable from the screen.

26. In a hammer mill, a housing, said housing having a lower arcuate opening for discharge of material, an arcuate screen, movable into a lower position to cover said opening and into a higher reserve position exteriorly of the housing, guide means for directing travel of the screen between the two positions, motor means for moving the screen between the two positions, including a pair of endless belts attached to said screen, and means to drive the belts in unison.

27. In a hammer mill, a housing, a screen which is one of a plurality of interchangeable screens insertable therein and removable therefrom, means attached to the housing for supporting the screens exteriorly thereof, an opening in the housing into which a screen may be inserted, a mechanism for translating each screen into the opening, motor means in common for operating the translating mechanisms, a slip clutch driving connection between the motor

and each translating mechanism, said clutch being adapted to transmit a limited amount of torque, a selected screen moving into the opening, and means for holding the reserve screens immovable against the pull of their respective slip clutches, said means being a latch in engagement with each of the reserve screens.

28. The combination as cited in claim 27 wherein the latch is disengaged from the selected screen by solenoidally operated means, the disengagement being made prior to removal of the inserted screen.

29. The combination as cited in claim 27 which includes means for releasing the latch from the selected screen to allow movement into the mill, said means being a solenoid.

30. In a hammer mill of the type that employs interchangeable grading screens, a housing, a discharge outlet in the periphery of the housing, said outlet having border elements adapted to seat a screen, a screen positioned over the outlet, motor means including an oscillatable element for clamping the positioned screen to the border elements, said means also being adapted to release the screen, and means for timing the releasing and clamping operations, said means including the oscillatable element.

31. The combination as cited in claim 30 wherein the screen-clamping mechanism includes means for spring-urging the clamped screen against the border elements of the peripheral opening, said means being compressed when screen is clamped.

32. The combination as cited in claim 30 wherein the means for actuating the screen-clamping mechanism includes a torque-responsive slipclutch, said clutch being adapted to slip when the screen is clamped.

33. In a hammer mill, a housing, said housing having an arcuate outlet for discharge of material, an arcuate screen, movable into a lower position to cover the outlet and into a higher reserve position exteriorly of the housing, an opening in the housing into which the screen may be inserted, guide means exteriorly of the housing for directing the travel of the screen in an arcuate path between the two positions, said means being supported by the housing, and motor means for moving the screen between the two positions.

34. In a hammer grinding mill, a housing, said housing having a grinding compartment, an arcuate outlet in periphery of said compartment for discharge of material, said outlet having border elements adapted to seat an arcuate screen, a compartment that receives efflux from the discharge outlet, an opening in the efflux compartment through which a screen may be inserted and withdrawn, a screen supported exteriorly of the efflux receiving compartment by means attached to the mill structure, means for inserting the screen into the efflux receiving compartment and positioning it over the discharge outlet, means for clamping the positioned screen to the border elements of the discharge outlet, means for closing the screen opening after the screen is positioned, and motor means in common for actuating the said inserting, clamping and closing means in sequence.

35. In a hammer mill, a housing into which is inserted a grading screen, said screen being one of a plurality of similar screens interchangeable therewith and positionable in substitution therefore, motor means for positioning a selected screen in substitution for the inserted screen,

manually operated controls for selecting a reserve screen, a source of electrical energy for the motor, electrical controls for starting the motor, and means for operating said starting controls, said means being the manually operated selecting controls.

36. In a hammer mill, a mill structure including a housing, an arcuate screen which is one of a plurality of similar interchangeable screens insertable in the housing and removable therefrom, an opening in the housing into which a screen may be inserted, a selected screen inserted in the opening and having one edge projecting therefrom, means for supporting the reserve screens exteriorly of the housing and in overlapping relation with the projecting edge of the inserted screen, said supporting means being the mill structure, a mechanism for withdrawing the inserted screen from the opening while the reserve screens are standing still, and means for supporting said mechanism, said means being attached to the mill structure.

37. In a hammer-grinding mill or the like including a housing into which is inserted a grading screen, said screen being one of a plurality of similar reserve screens interchangeable therewith and positionable in substitution therefor, a reversible screen-positioning mechanism for interchanging a selected screen with the inserted screen, motor means for actuating the screen-positioning mechanism, a source of electrical energy for the motor, and electrical controls for simultaneously selecting the reserve screen and starting the motor, said controls including a manually operated pushbutton switch associated with each screen and a normally open switch which is momentarily closed by the selected pushbutton to energize a holding coil that starts the motor.

38. In a hammer mill or the like including a housing, an arcuate screen which is one of a plurality of similar interchangeable screens insertable in the housing and removable therefrom, means for supporting the screens exteriorly of the housing in fixed relation with each other, said means including a stationary track, an opening in housing through which a selected screen of the plurality may be translated, a mechanism including an oscillatable element carried by mill structure for translating the selected screen

50

into the opening while the reserve screens are standing still, said mechanism being reversible for removal of the inserted screen, and stationary means attached to the mill structure for limiting travel of the outgoing screen.

39. In a hammer mill including a housing, an arcuate screen which is one of a plurality of similar interchangeable screens removable from and insertable therein, means for supporting the screens exteriorly of the housing in a fixed order with respect to each other, said means including a stationary track, an opening in the housing into which a selected screen may be inserted, a reversible mechanism for translating the selected screen into the opening while the reserve screens are standing still, said mechanism also being adapted for removing screen, means for limiting movement of the screen-translating mechanism in both directions, said means being stationary elements associated with the mill structure, and means for limiting travel of the screen, said means being the screen-translating mechanism.

40. In a hammer mill, a housing, a screen which is one of a plurality of interchangeable screens insertable therein, means for supporting the reserve screens exteriorly of the housing, said means being attached to the housing, an opening in housing into which a selected screen may be inserted, a reversible mechanism including an oscillatable element for inserting the selected screen, means for supporting the reversible mechanism, said means including a stationary track, guide means for directing travel of moving screen in a fixed path, said means including the track, and means for actuating the reversible mechanism while the reserve screens are standing still.

ARTHUR G. NICKLE.
